(57) **CLAIM**

The ornamental design for a Christmas tree, as shown and described.

DESCRIPTION

FIG. 1 is a front, right and top perspective view of a Christmas tree showing my new design;

FIG. 2 is a rear, left and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged portion view labeled, "9," in FIG. 1. The long dashed, short dashed broken lines depict boundaries of the enlarged portion view of FIG. 9 in FIGS. 1 and 9 and form no part of the claimed design.

The even dashed broken lines shown in the drawings represent portions of the Christmas tree that form no part of the claimed design.
